MATTRESS AND METHOD OF MAKING
THE SAME

Edward L. Bronstien, St. Paul, Minn.

Application October 30, 1933, Serial No. 695,834

3 Claims. (Cl. 5—360)

It is the object of this invention to provide a novel and inexpensive mattress of the type having edge rolls which are concealed within the mattress.

5 A particular object is to provide in a mattress, having a padded inner spring body, edge rolls formed from portions of the top and bottom padding material and so connected to the spring body and boxing that separation of the rolls from the padding is effectively guarded against.

10 Another object is to provide a mattress having edge rolls which are formed and attached to the boxing by stitches entirely concealed within the mattress.

15 A further object is to provide a novel method of forming a mattress whereby economies in the manufacturing operation and in the use of fabrics are effected and internal edge rolls are so formed as to leave the boxing and top and bottom ticking smooth and without indentations.

20 The invention will be best understood by reference to the accompanying drawings in which,

Figure 1 is a fragmentary, vertical section through the spring body and inner lining fabric 25 and layers of padding and illustrating my preferred method of forming the edge rolls;

Fig. 2 is a similar section with the boxing applied to the filling body;

Fig. 3 is a plan view, partially broken away, 30 showing a part of the filling and corner roll before the application of the boxing, and

Fig. 4 is a part vertical section and part elevation illustrating the completed mattress.

35 A spring body of common or suitable type constitutes the principal filling for the mattress. As illustrated, this body comprises a multiplicity of upholstery springs 5 connected together at the margins of the mattress by helical springs 6 and within the body by helical springs 7 (Figs. 1 and 40 3) extending parallel to each other. Upon the top and bottom surfaces of the spring body are laid lining sheets 8 of suitable fabric. These sheets have a greater superficial area than the spring body so that the marginal portions of 45 each sheet are adapted to be utilized in forming edge rolls 9 extending around the mattress for squaring the top and bottom corners. Layers of padding 10 are placed on the outer surfaces of the sheets 8 respectively and are made to project 50 at the edges sufficiently to afford the stuffing for the corner rolls 9. The projecting edge portions of the padding 10 are then compressed and confined by rolling over the edges of the sheets 8 and by applying ties 11 extending through said lining sheets and padding 10 and engaging the mar-

ginal springs 5 and 6. In this manner the rolls 9 are made integral with the padding 10 and sheets 8 and in the same operation the rolls are secured in proper position for direct support from the marginal springs 5.

5 The resulting structure is ready for the application of the boxing, as illustrated in Fig. 2. The boxing comprises an outer ticking strip 12, an inner fabric strip 13 and suitable quilting formed by stuffing material 14 and parallel rows 10 of stitches 15 extending horizontally around the mattress. To attach the boxing to the previously formed structure, rows of stitches 16 are applied to connect the upper and lower edges of the strip 13 to the upper and lower edge rolls 9 15 respectively. It will be understood that the outer strip 12 is separable from the upper and lower margins of the strip 13 to allow access to the outer surface of the latter for the sewing of the stitches 16.

20 To complete the mattress, as shown in Fig. 4, additional layers of padding 17 are applied to the outer surfaces of the padding 10 and then the top and bottom ticking or cover sheets 18 are applied and their edges secured to the upper 25 and lower edges of the strip 12 by forming the usual or suitable seams 19 while the outer boxing strip is placed under tension in its straight vertical position.

Among the advantages secured by my invention, the following will now be understood. The corner rolls are formed from integral portions of the top and bottom lining fabrics and padding material and such sheets and padding are essential irrespective of whether the edge rolls are 35 provided. In other words, there are no extra strips, sheets or separate bodies of filling required for the edge rolls. The edge rolls are so confined directly between the supporting springs and corners of the mattress that unusually square 40 corners result and separation of the rolls from the top and bottom padding is rendered unlikely because of the unitary form of rolls and padding. All stitches forming the corner rolls and connecting the same to the boxing and spring are concealed within the mattress and the outer surfaces of the boxing and corner portions of the top 45 and bottom are unusually straight and free from indentations.

Having described my invention, what I claim 50 as new and desire to protect by Letters Patent is:

1. A mattress having in combination; a body of upholstery springs resiliently joined together and having at its upper and lower margins flexi- 55

ble tie members extending longitudinally of the margins and constituting the sole connection between springs around the edges of said body, a pair of lining sheets respectively overlying the top and underlying the bottom of said body and each of said lining sheets having flaps adapted to project outward from said tie members, layers of loose, felt-like padding adjacent to said lining sheets, said flaps being folded upon the margins 5 of said padding, ties passing through said flaps at a multiplicity of spaced points upon the outer margins of said layers of padding and engaging said longitudinally extending tie members and forming edge rolls from compressed integral edge 10 portions of said padding material, a quilted boxing having inner and outer fabric strips with padding between them, means connecting the upper and lower edges respectively of the inner strip of said boxing to said edge rolls and top and bottom cover sheets having their edges secured to the upper and lower edges respectively of said outer boxing strip.

2. A mattress having in combination, a body of upholstery springs resiliently joined together and having at its upper and lower margins flexible tie members extending longitudinally of the margins and constituting the sole connection between springs around the edges of said body, a pair of lining sheets respectively overlying the top and underlying the bottom of said body and each of said lining sheets having flaps adapted to project outward from said tie members, layers of loose, felt-like padding overlying the top and underlying the bottom surfaces respectively of said lining sheets, said flaps being folded upon the marginal portions of said padding, ties securing said flaps at a multiplicity of spaced points upon the outer margins of said layers of padding, 15

said ties passing through said flaps and margins and engaging said longitudinally extending tie members and forming edge rolls from compressed integral edge portions of said padding material, a quilted boxing having inner and outer fabric strips with padding between them, means connecting the upper and lower edges respectively of the inner of said boxing strips only to said edge rolls and top and bottom cover sheets having their edges secured to the upper and lower edges respectively of said outer boxing strip. 10

3. A mattress having in combination, a body of upholstery springs resiliently joined together and having at its upper and lower margins flexible, helical springs extending longitudinally of the margins, a pair of lining sheets overlying the top and underlying the bottom of said body directly and each having flaps adapted to project outward from said helical springs, layers of loose padding overlying the top and underlying the bottom respectively of said lining sheets, said flaps being folded to embrace the margins of said padding, ties securing said flaps upon the outer margins of said layers of padding and engaging said helical springs and forming edge rolls from compressed edge portions of said padding material directly above and below said helical springs, a quilted boxing having inner and outer fabric strips with padding between them, means connecting the upper and lower edges respectively of said inner strip of said boxing to said edge rolls, said inner fabric boxing strips being secured to said outer boxing strips along lines extending parallel and adjacent to said helical springs and top and bottom cover sheets having their edges secured to the upper and lower edges respectively of said outer boxing strip. 15
